Inventor
JAY S. FOSKY

By

Ch. Harten Attorney

UNITED STATES PATENT OFFICE.

JAY S. FOSKY, OF SANDUSKY, OHIO.

FEED-WATER HEATER.

Application filed March 20, 1922. Serial No. 545,145.

To all whom it may concern:

Be it known that I, JAY S. FOSKY, a citizen of the United States, residing at Sandusky, in the county of Erie and State of Ohio, have invented certain new and useful Improvements in Feed-Water Heaters, of which the following is a specification.

This invention relates to feed water heaters for steam boilers, and more particularly for locomotive boilers.

An object of the present invention is the provision of a feed water heater capable of use on locomotive boilers, wherein the waste gases of combustion may be employed for preheating the water on its passage to the boiler.

Where a boiler is not provided with a feed water heater, the water is delivered to the boiler cold and it is then necessary to raise it to boiling temperature in the boiler. Various types of feed water heaters have heretofore been employed in connection with steam boilers, and such feed water heaters are generally a separate and independent apparatus and are incapable of use on locomotive boilers due to lack of space.

In the present invention, I arrange a plurality of tubes beneath the boiler and connect these tubes to the source of supply.

Suitable means are provided for passing the products of combustion from the boiler around these tubes to preheat the feed water.

By means of the construction provided, the feed water of a boiler is preheated from a source of heat that is usually wasted.

In the specific form of the invention disclosed, the heating tubes of the feed water heater are arranged in loops and a baffle plate is extended between the loops to force the gas from the fire box to travel over each section of tubes on each side of the baffle plate.

In the accompanying drawings, I have shown one embodiment of the invention.

In this showing:

Figure 1 is a central vertical sectional view of a locomotive boiler showing the invention applied.

Figure 2 is a transverse vertical sectional view on line 2—2 of Figure 1.

Figure 3 is a similar view on line 3—3 of Figure 1.

Figure 4 is a horizontal sectional view on line 4—4 of Figure 3, and,

Figure 5 is a detail vertical sectional view on line 5—5 of Figure 3.

Referring to the drawings, the reference numeral 1 designates the water compartment of a locomotive boiler provided with suitable fire tubes 2. The products of combustion from a fire box (not shown) pass over an arch or bridge 3, through the fire box to a smoke compartment 4, at the forward end of the locomotive. Heretofore it

has been customary to permit direct passage of the products of combustion through the smoke compartment to a stack 5. In the present invention, I provide a vertical baffle plate 6, arranged in the smoke compartment and connected to a horizontal baffle

plate 7, extending substantially the entire length of the boiler and spaced from the bottom. The feed water heater consists of a plurality of pipes 8, extending from the smoke box to a point adjacent the other end of the boiler and then looped as at 9. As

shown, one section of each of the pipes 8 is arranged below the horizontal baffle plate 7, and is connected to a similar section above the baffle plate 7 by loop 9. An intake

header 10 is arranged forwardly of the baffle plate 6, and is connected to a suitable source of supply by means of a pipe 11. The lower sections of the pipes 8 are ex-

tended upwardly at their forward ends, as at 12, and communicate with this header (see Figures 4 and 5). A similar outlet

header 13 is arranged on the opposite side of the baffle plate and is connected to the boiler by a pipe 14. The upper sections of

pipes 8 are connected to this header by vertical portions 15, extending through openings in the bottom of the header.

In operation, the products of combustion pass through the boiler in the usual manner, heating the water to develop steam. The products of combustion enter the smoke chamber at a relatively high temperature and instead of permitting them to pass im-

mediately to the stack, I utilize the heat of these products of combustion to preheat the feed water. By means of baffle plates 6 and

7, the products of combustion are forced to flow beneath the boiler over the baffle plates 7 and then return to the smoke chamber beneath the baffle plates 7, preheating the water in the pipes 8.

While the invention is illustrated in con-

nection with a fire tube boiler, it will be apparent that it may also be used in connection with a water tube boiler.

It is to be understood that the form of my invention herewith shown and described is to be taken as a preferred example of the same, and that various changes in the shape, size, and arrangement of parts may be resorted to without departing from the spirit 10 of the invention or the scope of the subjoined claims.

Having thus described my invention, I claim:

1. In a steam boiler, a substantially vertical baffle plate arranged in the smoke box, an intake header and an outlet header arranged on opposite sides of said baffle plate, a series of pipes connected to each of said headers and extending beneath the water 15 compartment of the boiler, and a substantially horizontal baffle plate extending from the lower end of said vertical baffle plate and arranged adjacent said pipes whereby 20

the products of combustion are forced to flow under said horizontal baffle plate and around said pipes.

2. In a steam boiler, a substantially vertical baffle plate arranged in the smoke box, an intake header arranged on one side of said baffle plate remote from the water compartment of the boiler, said header being connected to a source of supply, an outlet header arranged on the opposite side of said baffle plate adjacent the water compartment of the boiler and communicating therewith, a series of pipes having their opposite ends connected to said headers, said pipes being extended beneath the water compartment of the boiler and provided with loops adjacent the remote end of the water compartment, 30 and a substantially horizontal baffle plate arranged adjacent said pipes.

In testimony whereof I affix my signature.

JAY S. FOSKY.
